UNITED STATES PATENT OFFICE

125,138

DESIGN FOR A PORTABLE BAR

Clarence May, Chicago, Ill., assignor to Porto-Bar,
Inc., Chicago, Ill., a corporation of Illinois

Application May 11, 1940, Serial No. 92,301

Term of patent 7 years

To all whom it may concern:

Be it known that I, Clarence May, a citizen of the United States and resident of Chicago, in the county of Cook and State of Illinois, have invented a new, original, and ornamental Design for a Portable Bar, of which the following is a specification, reference being had to the accompanying drawing, forming a part thereof.

Fig. 1 is a top plan view of a portable bar, showing my new design.

Fig. 2 is a side elevational view of the same, the opposite side being the same as the view shown in Fig. 2.

Fig. 3 is an end elevational view of the same. The characterizing features of the design reside in a portable bar of the configuration shown, having raised panels in the sides and handles thereof, and having openings of varying size in the top thereof arranged as shown.

I claim:

The ornamental design for a portable bar, substantially as shown and described.

CLARENCE MAY.
